UNITED STATES PATENT OFFICE.

PHILIP BERNARD, OF JEFFERSON, SOUTH DAKOTA

HOG-WATERER.

1,035,306.

Specification of Letters Patent. Patented Aug. 13, 1912.

Application filed December 4, 1911. Serial No. 663,746.

To all whom it may concern:

Be it known that I, PHILIP BERNARD, a citizen of the United States, residing at Jefferson, in the county of Union and State of South Dakota, have invented a new and useful Hog-Waterer, of which the following is a specification.

The invention relates to improvements in hog waterers.

10 The object of the present invention is to improve the construction of hog waterers and analogous stock watering devices, more especially the construction shown and described in Patent No. 843,925, granted to me Feb. 12, 1907, and to enable an ordinary lamp to be employed for heating the water and to provide a metallic chimney for the same, having heat outlets located beneath the tank and also beneath the bottom of the 20 exterior drinking trough, so as to prevent the water contained within the trough from freezing in any kind of weather.

With these and other objects in view, the invention consists in the construction, and 25 novel combination of parts hereinafter fully described, illustrated in the accompanying drawing, and pointed out in the claim here-to appended; it being understood that various changes in the form, proportion, size 30 and minor details of construction, within the scope of the claim, may be resorted to without departing from the spirit or sacrificing any of the advantages of the invention.

35 In the drawing:—Figure 1 is a vertical sectional view of a hog waterer, constructed in accordance with this invention. Fig. 2 is an enlarged detail sectional view, illustrating the arrangement of the heating 40 means. Fig. 3 is a vertical longitudinal sectional view of the metallic chimney.

Like numerals of reference designate corresponding parts in all the figures of the drawing.

45 In the accompanying drawing in which is illustrated the preferred embodiment of the invention, 1 designates an outer metallic jacket of cylindrical or other form, constructed of galvanized sheet metal or other 50 suitable material, and provided with a removable cover 2 of conical form, and equipped at its interior with a strainer 3 and adapted to be removed and inverted to form a funnel for filling an interiorly arranged 55 tank 4. The tank 4, which is also constructed of galvanized sheet metal, or other

suitable material, is spaced from the top, bottom and walls of the jacket by an intervening air space, which enables the tank to be enveloped in warm air, whereby the tank 60 is rendered easy to heat and rapid radiation of heat from the tank prevented. The tank may be supported by brackets 5, or other suitable means, suitably secured to the interior of the jacket, but other supporting 65 means may, of course, be employed. The tank is also provided with a conical or funnel-shaped top 6, which has a central opening from which depends a filling tube 7, preferably formed of gas pipe or other 70 tubular metal, and supported in position by a nut 8, arranged upon the top of the tank. The top of the tank is equipped with a suitable vent 9, having a screw cap or other suitable closure adapted to close the opening 75 of the vent after the tank has been filled. The cover 2 has a central opening and is provided with a short tube 10 of a length to extend into the filling tube when the cover is inverted for use as a funnel. The 80 strainer 3, which preferably consists of wire gauze or woven wire, is adapted to prevent the tubes from becoming clogged.

On the exterior of the jacket is secured a trough 11, consisting of a piece of sheet 85 metal or other suitable material, bowed or bent to form a front portion and sides, the latter being secured at their edges to the outer face of the jacket. The trough is provided with a horizontal partition 12, 90 located at an intermediate point between its top and bottom and in substantially the plane of the bottom of the tank and forming an upper drinking compartment 13 and a lower space or compartment 14, located at 95 an opening 15 in the jacket and communicating with the interior of the latter at the space beneath the tank. The tank is connected with the trough by a short pipe or nipple 16, piercing the tank and the jacket 100 and suitably secured to the same. The short pipe or nipple forms an outlet for the water and is located below the upper edge of the drinking compartment of the trough, so as to be submerged by the water within the 105 latter, the hog waterer being automatic in its action, water flowing through the outlet into the trough as it is consumed in the latter.

Within the lower portion of the jacket in 110 the space below the tank is arranged a lamp 17, having an ordinary burner 18 and

equipped with a metallic chimney 19 of approximately T-shape, consisting of a lower vertical portion and an upper horizontal portion. The lower vertical portion is 5 clamped upon the gallery of the burner by the screw 20 thereof in the usual manner, and the horizontal top portion forms arms, extending in opposite directions from the vertical portion, and having end walls 21 provided with openings 22 of sufficient size 10 to produce the necessary draft and also to throw a sufficient heat under the trough to prevent the water from freezing in all kinds of weather. One of the horizontal arms of 15 the metallic chimney extends through the opening 15 into the lower space or compartment 14 of the trough and the outlet 22 at this end of the horizontal portion of the chimney is located beneath the horizontal portion 12, and discharges heat 20 against the lower face of the same, so that there is no liability of the water within the drinking compartment of the trough freezing and interfering with the operation of 25 the device. The other horizontal arm of the metallic chimney extends in the direction of the center of the bottom of the tank and discharges heat against the latter. The tank and the main portion of the chimney are 30 located within the space below the tank, and there is sufficient heat to prevent the water therein from freezing. The metallic chimney is equipped at one side with an opening 23, which is covered by a plate or piece 24 35 of isinglass or other transparent material, so that the flame of the lamp will be visible from the exterior of the metallic chimney. The lower portion of the jacket is equipped with a hinged door 25, located opposite the

sight apertures 23 of the metallic chimney, 40 and adapted to afford access to the space below the tank for adjusting the wick of the lamp.

Having thus fully described my invention, what I claim as new and desire to set 45 apart by Letters Patent, is:—

An apparatus of the class described comprising an outer jacket having an opening, a tank located within the jacket above the said opening, an outer metallic trough 49 mounted on the exterior of the jacket and covering the opening thereof and provided at an intermediate point between its top and bottom with a horizontal partition 55 forming an upper drinking compartment and a lower space or compartment located at the said opening and communicating with the interior of the jacket, an outlet connecting the tank with the drinking compartment of the trough, and a lamp located within the outer jacket below the tank and provided with an approximately T-shaped metallic chimney forming opposite horizontal arms provided with end walls having apertures, one of the arms extending through the opening of the jacket into the space below the said partition with its 60 outlet discharging beneath the same, the other arm being extended inwardly toward the center of the bottom of the tank with its 65 outlet discharging beneath the latter.

In testimony, that I claim the foregoing as my own, I have hereto affixed my signature in the presence of two witnesses.

PHILIP BERNARD.
